UNITED STATES PATENT OFFICE.

JOHN R. KUNZELMAN, OF DULUTH, MINNESOTA.

AUXILIARY STEP FOR CAR-PLATFORMS.

1,141,064.

Specification of Letters Patent.

Patented May 25, 1915.

Application filed March 6, 1915. Serial No. 12,515.

To all whom it may concern:

Be it known that I, JOHN R. KUNZELMAN, a citizen of the United States, residing at Duluth, in the county of St. Louis and State of Minnesota, have invented certain new and useful Improvements in Auxiliary Steps for Car-Platforms; and I do hereby declare the following to be a full, clear, and exact description of the invention, such as will enable others skilled in the art to which it 5 appertains to make and use the same.

My invention relates to improvements in auxiliary steps for car platforms of the type disclosed and claimed in my Letters Patent of the United States, No. 1,070,565, issued 15 of date November 25th, 1913, entitled "Car step," and No. 1,089,481, issued of date March 10th, 1914, entitled "Auxiliary step for car platforms," and in my co-pending application, entitled "Auxiliary step for car platforms," filed June 29th, 1914, under Serial Number 847,828, and formally allowed 20 August 26th, 1914.

To the above end, the invention consists of 25 the novel devices and combinations of devices hereinafter described and defined in the claims.

In the accompanying drawings, which 30 illustrate the invention, like characters indicate like parts throughout the several views.

Referring to the drawings: Figure 1 is a fragmentary view in end elevation, of a car body and vestibule, having applied thereto in working position the improved auxiliary step; Fig. 2 is a view, in side elevation, of the parts shown in Fig. 1, some parts being broken away, some parts being shown in section, and some parts being shown in different positions by means of broken lines; 35 Fig. 3 is a view corresponding to Fig. 1, but showing the auxiliary step folded and the trap door closed, some parts being broken away and some of the exposed parts being shown in section; Fig. 4 is a view, principally in side elevation of the parts shown 40 in Fig. 3, some parts being sectioned on the line $X^4 X^4$ of Fig. 3. Fig. 5 is a right end elevation of the parts shown in Fig. 2, some parts being broken away; Fig. 6 is a view in 45 longitudinal vertical section taken on the line $X^6 X^6$ of Fig. 5; Fig. 7 is a plan view of the left-hand toggle lever, on an enlarged scale, provided for raising and lowering the auxiliary step, some parts being shown in 50 different positions by means of broken lines; Fig. 8 is an outside side elevation of the

parts shown in Fig. 7; Fig. 9 is a detail view with some parts sectioned on the line $X^9 X^9$ of Fig. 8; Fig. 10 is a detail view, principally in section, taken on the line $X^{10} X^{10}$ of Fig. 8; Fig. 11 is a view, partly in side elevation and partly in longitudinal section, taken on the line $X^{11} X^{11}$ of Fig. 7; Fig. 12 is a view in vertical section, taken on the line $X^{12} X^{12}$ of Fig. 4 and also showing, in section, a housing for the parts of the auxiliary step operating devices, located under the platform steps, some parts being indicated in different positions, by means of broken lines; Fig. 13 is a detail view partly in elevation and partly in vertical section taken on the line $X^{13} X^{13}$ of Fig. 3; Fig. 14 is a view corresponding to Fig. 13 with the exception that some parts are shown in different positions; Fig. 15 is a view of a modification of the parts shown in Fig. 1; Fig. 16 is a side elevation of the part shown in Fig. 15, some parts being broken away and some of the exposed parts being shown in section; Fig. 17 is a view in the side elevation of a modification of the parts shown in Fig. 13; and Fig. 18 is a view partly in edge elevation and partly in section taken on the line $X^{18} X^{18}$ of Fig. 17.

Referring first to the construction shown 85 in Figs. 1 to 14 inclusive: Of the parts of the car illustrated, it is only necessary to note the body 1, vestibule 2, main steps 3, secured between side walls 4, and leading to the vestibule platform 5, and a trap door 6. 90 This trap door 6 is hinged at 7 for vertical swinging movement to and from operative position, and is provided for covering the steps 3 to form an extension of the platform 5 when the vestibule door, not shown, is 95 closed. Any of the customary means may be provided for holding the trap door open, such as springs incorporated in the hinges 7, or a latch secured to the vestibule and engageable with the free edge of the trap 100 door 6.

As is well known, the lower car step is usually located so high above the road-bed that it is practically impossible to step upon the same without the use of a stool, unless an elevated platform is provided at the station. To take the place of these removable stepping stools, I provide an improved auxiliary step mounted for raising and lowering movements from an inoperative position to an 110 operative position, and vice versa.

The improved auxiliary step comprises a

tread 8, having vertically extended end and back flanges 9 and 10 respectively and a riser 11 in the form of a pair of parallel supporting links. The upper ends of these links 11 are pivotally secured at 12 to the side walls 4, and the lower ends thereof are pivotally secured to the end flanges 9 in a position to be engaged by the flange 10, which affords a stop to limit the unfolding movement of the tread 8.

A pair of upwardly buckling toggle levers 13 and 14 are provided for moving the auxiliary step to and from operative positions and to hold the same locked in an operative position. The outer ends of the lower arms of the levers 13 and 14 are provided with inwardly projecting trunnions 15, journaled in bearings 16, secured to the under side of the tread 8. The outer ends of the upper arms of the levers 13 and 14 terminate in hubs 17, keyed to the ends of a rock shaft 18, journaled in the side walls 4.

A coiled spring 19, mounted on the rock shaft 18, tends to rotate said rock shaft in a direction to straighten the toggle levers 13 and 14. One end of this spring 19 is anchored to a radially projecting arm 20 rigidly secured to the rock shaft 18, and the other end thereof is anchored to the disk 21, loosely journaled on said rock shaft. The disk 21 is secured against rotation with the rock shaft 18 by a spring latch 22 secured to the side wall 4, adjacent the car body 1, and with its free end arranged to enter any one of a multiplicity of circumferentially spaced perforations 23, formed in said disk. Obviously, by releasing the latch 22 from the disk 21, said disk may be rotated, by any suitable tool on the rock shaft 18 for the purpose of placing the coiled spring 19 under the desired tension.

To prevent the auxiliary step 8 from unfolding or opening too fast, under the action of the coiled spring 19, is provided a retarding device in the form of a dash pot 24 and a coöperating stem equipped piston 25. The outer end of the stem of the piston 25 is pivoted at 26 to the arm 20, and the dash pot 24 is suspended, by a pin 27, from a bearing 28 on one of the steps 3 for vertical swinging movement, transversely of the rock shaft 18. The action of the retarding device may be regulated in the customary manner by a cock 29, located in the bottom of the dash pot 24.

At the joint of each toggle lever 13 and 14 is a shield, or saddle, 30 and which provides the joint or connection between the arms of the respective toggle lever. The inner ends 60 of the arms of the toggle levers 13 and 14 are embraced by the sides of the respective shields 30, and are rigidly secured thereto by rivets 31. The inner ends of the lower arms of the toggle levers 13 and 14 are also embraced by the sides of the respective shields

30 and are pivotally secured thereto by offset pivots 32, which allow the buckling and straightening movements of said toggle levers. Obviously, the shields 30 afford stops to limit the straightening movements of the 70 toggle levers 13 and 14, and also prevent the placing of nails or other obstructions in the joints of said toggle levers to prevent their successful operation.

Projecting horizontally outward from 75 each bearing 16 is a stop pin 33, arranged to engage the lower edge of the lower arm of the respective toggle lever when the tread 8 is in an operative or lowered position. The purpose of these stops 33 is to assist in 80 supporting the tread 8 in an operative position and to cause a positive folding movement thereof during the initial buckling movement of the toggle levers 13 and 14.

Fulcrumed to the inner face of the outer 85 wall of the vestibule 2, just above the platform 5, is a hand lever 34 having pivoted thereto a long depending rod 35. This rod 35 works freely through an aperture in the platform 5 and its lower end is bent laterally to afford a horizontally extended finger 36, which projects under the joint of the toggle lever 13 in a position to be engaged thereby under certain conditions, as will presently appear. The lower end portion of 90 the rod 35, above the finger 36, is mounted for vertical sliding movement in a bearing 37 secured to the adjacent side wall 4.

When the auxiliary step 8 is raised into an 100 inoperative position, under the action of the spring 19, the same is automatically locked in this position by a depending spring latch hook 38, having a cam surface 39. The upper end of the arm of the latch 38, is secured to the under side of the vestibule floor 5 for lateral yielding movement, transversely of the toggle lever 13, and its cam surface 39 is arranged to be engaged by said toggle lever during its buckling movement, and moved laterally thereby out of the path of movement of said toggle lever. After the toggle lever 13 has passed the lock hook 38, the same immediately returns to an operative position under said toggle lever and thereby holds said lever against straightening movement.

The latch hook 38 is moved laterally against its spring tension to release the buckled toggle lever 13 by a link 38^a and a loop 38^b. One end of the link 38^a is pivotally secured to a fixed bearing 38^c, and the other end thereof is pivotally secured to the rod 35. The loop 38^b embraces the arm of the latch hook 38 and is pivotally secured to the intermediate portion of the link 38^a. The bearing 38^c is secured to the adjacent side wall 4 and acts as a base of resistance for the link 38^a. In the operative position of the latch hook 38 and the lowered position of the rod 35, the pivotal connection be- 115 120 125 130

6 between the link 38^a and loop 38^b is vertically below the pivotal connection of said link with the bearing 38^c. By drawing upward on the rod 35, the link 38^a is moved into such a position as to carry the pivot point of the loop 38^b into horizontal alinement with the pivotal connection between the link 38^a and its bearing, and laterally away from the arm of the lock hook 38. As best shown in 10 Fig. 14, this movement of the loop 38^b carries the latch hook 38 to one side of the toggle lever 13 and thereby permits said toggle lever to be straightened.

15 When the lever 34 is raised to release the toggle lever 13 by the movement of the spring latch 38 into an inoperative position, the finger 36 is also raised. During the lowering movement of the step 8, the finger 36 is engaged by the toggle lever 13 at the limit of its straightening movement 20 and moved downward thereby together with the rod 35 and the lever 34. This downward movement of the rod 35 releases the spring latch 38 through the connections 25 38^a-38^b and allows said latch to automatically resume its operative position.

30 The auxiliary step may be simultaneously raised or lowered with the closing and opening movements of the trap door 6, or it 35 may be raised and lowered when the trap door 6 is locked open by a hand operated lever 40. This lever 40 is mounted for longitudinal sliding movements on the upper arm of the toggle lever 13, and has integrally formed with its inner end a pair of 40 guide lugs 41 which embrace the said upper arm with freedom for longitudinal sliding movement thereon. In the forward portion of the lever 40 is formed a longitudinally extended slot 42, within which works 45 a headed extension 43 on one of the rivets 31. The body of the extension 43 is somewhat larger in the diameter of the respective pin 31, to thereby afford a stop shoulder 50 which prevents the head of the extension 43 from being drawn onto the lever 40, and thereby prevents free sliding movement of said lever. When the lever 40 is not in use, the same is moved into an inoperative position, as best shown by full lines in Figs. 7 55 and 8, and when in an operative position the same is drawn into an extended position, as shown by dotted lines in Fig. 7, and which affords an extension of the upper arm 60 of the toggle lever 13. The purpose of mounting the levers 34 and 40 on the same side of the vestibule is to permit the lock hook 38 to be operated, and the tread 8 raised or lowered, by a person on the outside of the vestibule.

65 A jointed lever 44, arranged to fold in one direction only, is provided for raising and lowering the auxiliary step under the closing and opening movement of the trap door 6. This lever is extended through an

opening 45 in the inner side wall 4, and the pivot 46 of its joint is journaled in a metallic casing 47 for the opening 45. The short end of the lever 44 is connected to the intermediate portion of the upper arm of the toggle lever 14 by a link 48. This link is made longitudinally adjustable by screwing its upper end into a sleeve 49, which is pivotally secured to the short end of the lever 44 by a cotter pin 50. Obviously, by removing the cotter pin 50 and turning the sleeve 49 with respect to the link 48, said link may be lengthened or shortened at will. The outer end of the long end of the lever 44 is connected to the trap door 6 for pivotal and sliding movements by a pin 51 extended transversely therethrough, and having its ends mounted for pivotal and sliding movements in a longitudinally extended slot 52, formed in a recess bearing 53, secured to the under side of the trap door 6.

70 The rock shaft 18 and retarding devices 15 24 and 25, located under the steps 3, are inclosed by a housing 54, having a hinged door 55, affording access to the interior of 25 said housing.

25 Referring now to the construction illustrated in Figs. 15 and 16: The spring 19^a is arranged to work in an opposite direction from the spring 19, or in other words, the spring 19^a tends to buckle the toggle levers 13 and 14 and fold the auxiliary step 8. A hand lever 56, fulcrumed in a segmental casing 57, is provided for lowering the auxiliary step 8 against the tension of the spring 19^a. The segmental casing 57 is bolted to the floor 5 and is provided with a peripheral slot in which the lever 56 works and through which the hand piece of said lever projects. A link 58 connects the intermediate portion of the lever 56 with the joint of the toggle lever 13 and works through a vertical slot formed in the end sill of the car platform. The hand lever 56 is held in its two extreme positions by lock notches 59 formed in the periphery of the casing 57, and with which notches said lever automatically engages under a lateral springing action.

30 Normally the auxiliary step 8 is held in a folded position by the lever 56 and coöperating upper lock notch 59. To lower the step 8, the lever 56 is first moved laterally out of engagement with the upper lock notch 59 and then moved downward against the tension of the spring 19^a. The lever 56, upon reaching its lowermost position, automatically springs laterally into interlocking engagement with the lower lock 35 notch 59 and thereby secures step 8 in an operative position.

35 To release or fold the auxiliary step 8 it is only necessary to spring the lever 56 laterally out of engagement with the lower 40

lock notch 59 and the action of the spring 19^a will buckle the toggle levers 13 and 14, fold the step 8, and move the lever 56 into its uppermost position. The lever 56, upon reaching its uppermost position, will automatically spring laterally into interlocking engagement with the upper lock notch 59 and thereby secure the step 8 in its folded position.

10 By arranging the spring 19^a to fold the auxiliary step 8, all danger of the said step accidentally moving into an operative position, where the same projects outward from the sides of the car and is liable to cause 15 accidents when the train is moving, is eliminated. The lever 56 is so positioned that the same may be easily manipulated by a person standing either on the car steps or the station platform.

20 Referring now to the construction illustrated in Figs. 17 and 18:—This construction provides an extremely simple means for releasing the latch hook 38 from engagement with the lever 13 when said lever is 25 held thereby in a buckled position. In this construction the arm of the latch hook 38 is transversely bent to afford a cam surface 60. A relatively short hand lever 61 is fulcrumed at 62 to the adjacent side wall 4, 30 extends transversely of the arm of the latch hook 38, and is normally held in a plane just below the cam surface 60, so that when said lever is raised the same engages said cam surface and thereby cams the latch hook 38 35 into an inoperative position to release the engaged toggle lever 13.

The lever 61, forward of its contact with the cam 60, is pivotally secured to a laterally projecting lug 63 on the rod 35. By thus 40 connecting the lever 61 to the rod 35, the same is returned to a normal position, to release the spring latch 38 by the toggle lever 13 coming in contact with its finger 36, during its straightening movement. By 45 means of the lever 61 the latch hook 38 may be manipulated by a person standing on the station platform without having to reach up to the lever 34.

A U-shape bracket 64 is provided for preventing the lever 61 from springing laterally away from the arm of the latch hook 38 when said lever engages the cam 60 for releasing the latch hook. The bracket 64 embraces the lever 61 at a point between the 50 arm of the latch hook 38 and the rod 35 and is secured to the adjacent side wall 4.

What I claim is:—

1. The combination with a car platform, of a step leading to said platform, and 55 mounted for raising and lowering movements, means for operating said step, and an air check affording a retarding device of the piston and dash pot type, operative to check the movement of said step.

60 2. The combination with a car platform,

of a step leading to said platform, and mounted for raising and lowering movements, means for operating said step, including a rock shaft, and an air check affording a retarding device operative on said 70 rock shaft to check the movement of said step.

3. The combination with a car platform, of a step leading to said platform, and mounted for raising and lowering movements, means for operating said step, including a rock shaft, a spring tending to rotate said rock shaft in one direction, and a retarding device operative to check the 75 movement of said step.

4. The combination with a car platform, of a step leading to said platform, and mounted for raising and lowering movements, means for operating said step, including a rock shaft having an arm, and a spring 80 and a retarding device operative on said arm, the former tending to rotate said rock shaft and the latter tending to check the movement of said step.

5. The combination with a car platform, of a step leading to said platform, and mounted for raising and lowering movements, means for operating said step, including a rock shaft having an arm, a disk journaled on said rock shaft, a coiled spring 90 mounted on said rock shaft, and anchored at one end to said arm, and at its other end to said disk, and a lock operative on said disk 95 to hold the same in different set adjustments for varying the tension of said spring.

6. The combination with a car platform, of a step leading to said platform, and mounted for raising and lowering movements, means for operating said step, including a rock shaft having an arm, a disk journaled on said rock shaft, a coiled spring mounted on said rock shaft and anchored at one end to said arm, and at its other end to said disk, a lock operative on said disk to hold the same in different set adjustments 105 for varying the tension of said spring, and a retarding device of the piston and dash pot type, operative on said arm to check the movement of said step.

7. The combination with a car vestibule, main steps leading to the platform thereof, and a trap door hinged to said platform and covering said steps, of an auxiliary step mounted for raising and lowering movements, a toggle lever for operating said auxiliary step, an intermediately fulcrumed lever, and a longitudinally adjustable connection between said lever and one of the arms of said toggle lever, the other end of said intermediately fulcrumed lever being connected to said trap door, whereby said auxiliary step may be operated by the opening and closing movements of said trap door.

8. The combination with a car platform, of a step leading to said platform and 120

mounted for raising and lowering movements, a toggle lever for operating said step, and a lever extension carried by one of the arms of said toggle lever to partake of all 5 of the angular movements thereof.

9. The combination with a car platform, of a step leading to said platform, and mounted for raising and lowering movements, a toggle lever for operating said step, 10 and a lever extension slidably mounted on one of the arms of said toggle lever for movement to and from an operative position, said lever extension being provided for operating said toggle lever.

15 10. The combination with a car platform, of a step leading to said platform and mounted for raising and lowering movements, a toggle lever for operating said step, yielding means operative on said toggle lever 20 and tending to move the step into one of its extreme positions, a lever for moving the step into its other extreme position, against the action of said yielding means, and means, including said lever, for automatically 25 securing said step in one of its extreme positions.

11. The combination with a car platform, of a step leading to said platform and mounted for raising and lowering movements, 30 a toggle lever for operating said step, and means for automatically locking said toggle lever in a buckled position.

12. The combination with a car platform, of a step leading to said platform and 35 mounted for raising and lowering movements, a toggle lever for operating said step, means for automatically locking said toggle lever in a buckled position, and means for releasing said toggle lever when locked in 40 a buckled position.

13. The combination with a car platform, of a step leading to said platform and mounted for raising and lowering movements, a toggle lever for operating said step, 45 a spring latch for holding said toggle lever buckled, a hand lever having a connection for moving said spring latch into an inoperative position, and automatic means for resetting said spring latch.

50 14. The combination with a car platform, of a step leading to said platform and mounted for raising and lowering movements, a toggle lever for operating said step, yielding means operative on said toggle lever 55 and tending to move said step into one of its extreme positions, a lever for moving said step into its other extreme position, against the action of said yielding means, and means for automatically securing said lever in 60 either of its extreme positions.

15. The combination with a car platform,

of a step leading to said platform and mounted for raising and lowering movements, a toggle lever for operating said step, a spring tending to buckle said toggle lever 65 and raise said step, a latch lever for lowering said step against the tension of said spring, and means for automatically securing said latch lever in a locked position when said step is lowered. 70

16. The combination with a car platform, of a step leading to said platform and mounted for raising and lowering movements, a toggle lever for operating said step, a spring tending to buckle said toggle lever 75 and raise said step, a latch lever for lowering said step against the tension of said spring, and means for automatically securing said latch lever in either of its extreme positions. 80

17. The combination with a car platform, of a step leading to said platform and mounted for raising and lowering movements, a toggle lever for operating said step, a spring tending to buckle said toggle lever 85 and raise said step, a latch lever for lowering said step against the tension of said spring, a lock segment having a pair of circumferentially spaced lock notches with which said latch lever automatically interlocks, with a lateral springing action for securing said step in either of its raised or lowered positions. 90

18. The combination with a car platform, of a step leading to said platform and 95 mounted for raising and lowering movements, a toggle lever for operating said step, a yielding latch hook for holding said toggle lever in a buckled position and having a cam surface, and a lever operative on the 100 cam surface of said latch hook for moving the same into an inoperative position.

19. The combination with a car platform, of a step leading to said platform and mounted for raising and lowering movements, a toggle lever for operating said step, a yielding latch hook for holding said toggle lever in a buckled position and having a cam surface, a hand lever, arranged for engagement with the cam surface of said latch 110 hook for moving said latch hook into an inoperative position, and a connection carried by said lever and arranged to be operated by the straightening movement of said toggle lever for resetting said latch hook. 115

In testimony whereof I affix my signature in presence of two witnesses.

JOHN R. KUNZELMAN.
